UNITED STATES PATENT OFFICE

WARREN C. S. GRAHAM, OF NEW ORLEANS, LOUISIANA

HEAT EXCHANGE TUBING

Application filed April 5, 1929. Serial No. 352,712.

My invention relates broadly to an apparatus for improving the conduction of heat from hot gases, the products of combustion, or any other source, to a substance inside of a 5 pipe or tube conveying water, steam, oil, etc.

My invention employs a principle in which the gases of combustion are made to circulate around the tubes of my invention and thereby better transfer the heat to the substance in- 10 side the tube and at the same time retard the gases of combustion in order to extract from them the maximum of heat possible.

An object of my invention is to provide construction of tube by which maximum effi- 15 ciency may be obtained wherever the tube involving my invention is used or employed, particularly in connection with economizers, superheaters, in boilers or steam generators, in a tubing of the boiler or steam generator 20 proper, in water walls in furnaces or floors, or in any connection whatsoever therewith.

Another object of my invention is to pro- 25 vide a construction of water tube the outer surface of which is constructed to insure the maximum conduction of heat from the products of combustion circulating around the tube to the fluid circulating through the tube.

Still another object of my invention is to 30 provide a structure of tube for heat generating systems in which a member is integrally connected with the walls of the tube and is so shaped as to pocket or embrace the products of combustion to such an extent that maximum transfer of heat from the surface of the 35 tube to the interior walls of the tube is obtained.

My invention may also be employed to obtain a maximum of efficiency in cooling by 40 having the cooling agent, instead of the hot gases or products of combustion, pass over the exterior of the tube involving my invention. This cooling medium or agent may be liquid, air, or any other substance possessing cooling qualities.

My invention provides a most efficient 45 means of transferring heat from hot gases, after these gases have been passed through a boiler or steam generator, to water circu- 50 lating within the tube of my invention, such as is commonly employed in econo-

mizers. Hot gases or products of combustion, etc., passing parallel with the tube involving my invention, flow around the spiral ring on the outer surface of the tube and thereby transmit a maximum of heat transfer to the 55 substance inside of the tube. My invention may also be employed to advantage in waste type boiler installations. When employed as a superheater, the hot gases can be so baffled that they will pass the full length of the tube 60 involving my invention and thereby take advantage of the maximum amount of heat transfer with the minimum amount of loss caused by the slowing up of the gases.

My invention will be more clearly understood by reference to the accompanying drawings in which:

Figure 1 shows my invention applied to a superheater; Fig. 2 illustrates my invention applied to an economizer; Fig. 3 is an enlarged view partially in cross-section of a water tube constructed in accordance with my invention; Fig. 4 is an end view showing the water tube illustrated in Fig. 3; Fig. 5 illustrates a modified form of mounting for 70 the tube structure of my invention with respect to the standard type of boiler and tubing; Fig. 6 shows a modified form of water tube embodying my invention and applied to a water tube boiler system and showing the 75 path provided for the products of combustion around the tube of my invention; Fig. 7 is an enlarged side elevation showing the form of water tube illustrated in Fig. 6; and Fig. 8 is a plan view of the type of water tube 80 illustrated in Fig. 6.

Referring to the drawings it can be seen that the tubing involving my invention consists of a tube 12 having a ring 16 which may be continuous or broken forming a spiral 85 around the tube itself, which permits the gases or products of combustion to follow this spiral and to closely hug the tube on all sides and impart to the substance inside the tube the greatest amount of heat.

This tubing may be either slipped or pressed over the ordinary conventional boiler or steam generator tubing or any special tubing as illustrated in Fig. 5, or it may be made integral therewith forming a part 100

of the tube itself, as shown in the other views. This tubing may be made in sections or it may be employed in single lengths. It can be seen from the drawings that the 5 distance between the rings forming the spiral may be varied, depending upon the service in which the tube is employed and the rate of heat transfer desired. The distance to which these rings protrude from the tube it- 10 self may also be varied and is dependent upon the service in which the tube is employed.

The tube of my invention with a spiral ring thereon placed so the gases will pass from 15 one end of the tube to the other, or in the same direction or parallel with the tube itself, will cause these gases to follow the spiral ring, thereby increasing its efficiency. With the gases passing around the spiral ring the 20 maximum of heat is absorbed on all sides. This likewise applies to the cooling of a substance inside of the tube by passing of a cooling mixture over the tube.

Referring to the drawings in detail, Fig. 25 1 shows the application of my invention to a superheater in a boiler plant where heat from the furnace 3 is conveyed in the form of heat currents as indicated at 2 over the boiler tubes around baffle 5, recrossing the 30 boiler tubes around baffle 6 again recrossing the boiler tubes as indicated at 28 and passing up at stack 7. The boiler is shown at 1 and the superheater system at 4. The superheater employs the spirally arranged fins of 35 the tubes, as will be more fully described hereinafter.

In Fig. 2 I have shown the tubes of my 40 invention disposed vertically between header 8 and 9 to which are connected the inlet and outlet pipes 10 and 11. A multiplicity of tubes are employed, although I have indicated three such tubes at 12, 14 and 15. Each tube is provided with a spirally arranged flange 16, the spiral flange being 45 cupped or pocketed as shown at 18 and terminating in a rounded edge 17 by which the moving gases are made to adhere closely to the exterior walls of the tube.

In Fig. 5 I have shown the spiralled and 50 flanged tube 12 inserted over the usual boiler tube 30 for providing a heat conducting surface by which the heat may be conveyed by conduction into the inner tube 30, it being unnecessary in this instance to modify 55 the usual boiler tube 30.

In Fig. 6 I have shown my invention as applied to a water tube boiler which is heated 60 from the furnace hearth 19, the tubes being arranged in sets as represented at 20 and 21 separated by a baffle 31. The spiral flange on the tubes shown in Fig. 6 differs from the corresponding flange on the tube illustrated in Figs. 1 through 5 in that the portions of the spiral are pitched in the manner of 65 a screw with the peripheral edges thereof

terminating in relatively flat extensions. This structure permits the tube to be used either in a cooling system or a heating system with advantageous results.

By reason of the spirally arranged flange 70 24 on the tubes which I have referred to more clearly in Figs. 7 and 8 at 23, the gases are made to follow a course closely adhering to the walls of the boiler tubes, thereby imparting a high degree of heat to the tubes. The spiral formation of continuous flange 75 provides means for establishing a path for products of combustion around the several tubes and insures the heating of the contents of the tubes to the maximum degree.

It will be understood that variations in structure of the tube may be made within the scope of the appended claims without departing from the spirit of my invention.

What I claim as new and desire to secure 85 by Letters Patent of the United States is as follows:

1. In a furnace structure a multiplicity of fluid conducting tubes, each of said tubes having a spirally arranged flange on the exterior walls thereof, means for directing products of combustion over said tubes, the spirally arranged flanges being integrally connected with the walls of said tubes and cupped at the peripheries thereof toward the 90 walls of said tubes to establish a spiral path for heating gases immediately around the exterior walls of said tubes for imparting heat to said walls and the circulating fluid 95 therein.

2. In a furnace structure a multiplicity of parallel fluid circulating tubes, each of said tubes having an integrally formed spiral flange connected to the exterior walls thereof and cupped in the direction of said walls 100 for guiding products of combustion around said tubes in a spiral path immediately adjacent the exterior walls of the tubes for transferring heat to the walls of said tubes and to the fluid contents passing therethrough.

3. In a furnace structure a plurality of parallel fluid circulating tubes, each of said tubes having correspondingly aligned spiraled flanges integrally connected with the exterior walls thereof, said flanges having a 110 concave under surface directed toward the exterior walls of said tubes and disposed to establish a path for moving products of combustion immediately around said fluid circulating tubes for transferring heat from the exterior to the interior of said fluid circulating tubes.

4. In a water tube boiler, a tubular member constituting a fluid circulating path and a sleeve concentrically disposed about said tubular member, said sleeve carrying an integrally connected spiral flange thereon, said flange being cupped in a direction toward said sleeve to retain a zone of hot gases immediately around the sleeve for transferring 120 125 130

heat to the fluid circulating in said tubular member.

5. In a fluid circulating system, a tubular member for the passage of fluid, a sleeve concentrically disposed about said tubular member, said sleeve carrying a spirally disposed integrally connected flange thereon, said flange being substantially cupped to retain products of combustion in a heated zone immediately surrounding the sleeve for transferring heat to the walls of said tubular member.

10 6. In a fluid circulating system, a tubular member, a sleeve adapted to telescopically engage said tubular member, a spirally disposed flange integrally connected with the exterior walls of said sleeve, said flange having its peripheral edge directed opposite the normal path of flow for products of combustion around the sleeve for establishing a zone of heated gases immediately surrounding the sleeve and effecting a transfer of heat to the fluid passing through said tubular member.

15 20 In testimony whereof I affix my signature.
WARREN C. S. GRAHAM.
